UNITED STATES PATENT OFFICE.

MURT L. O'NEIL, OF WARLAND, MONTANA, ASSIGNOR TO ROBERT J. O'NEIL, OF SWISSHOME, OREGON.

GRAVEL BIN.

Application filed July 28, 1924. Serial No. 728,774.

To all whom it may concern:

Be it known that I, MURT L. O'NEIL, a citizen of the United States, residing at Warland, in the county of Lincoln and State of Montana, have invented certain new and useful Improvements in Gravel Bins, of which the following is a full, clear, and exact description.

In building gravel roads it is of paramount importance that the gravel, crushed stone or the like, which is to be spread on the road be maintained in a uniform mixture until ready for use. For instance, where gravel or the like is discharged from a chute into a large bin the larger pebbles or coarser stones will roll downward to the sides of the bin while the finer material will cling together in a pyramid. Consequently, when the material is hauled to the road being built or repaired certain loads will contain practically all fine material while others consist almost entirely of the larger size stones, so that the theoretically uniform mixture actually consists of a patch of coarse and a patch of fine.

It is an object of the present invention, therefore, to provide a bin or series of bins in which the gravel or crushed stone may be deposited and stored without piling the same in a single huge pyramid. To this end the invention consists of a series of compartment bins arranged in abutting relation combined with means whereby the gravel is fed to one compartment bin and as soon as that bin is filled the material continues to be fed to the next bin and so on until the entire series of bins is filled.

Other objects and advantages of the invention will be apparent from the following description when taken in connection with the accompanying drawings, in which,

Figure 1 is a side elevation of the complete device.

Figure 2 is a plan view thereof with parts broken away.

Figure 3 is a section taken on line 3—3 of Figure 2, and

Figure 4 is a section taken on line 4—4 of Figure 1.

Referring to the drawings more in detail the numeral 1 indicates a series of compartment bins arranged in abutting relation; and while four of these bins are shown on the drawing it will be obvious that a greater or less number may be used as found appro-

priate to the particular work at hand. Furthermore, instead of being built up of a plurality of individual compartment bins the apparatus may be built up as a single structure divided by transverse partitions into as many small bins as may be desired.

Each of the bins is composed of a central compartment 2 and two oppositely disposed side compartments 3, the latter being separated from the central compartment by vertical partitions provided with horizontal slots 4 and 5. As shown in Figure 3 of the drawings the slots 4 and 5 are located at different levels for a purpose to be described hereinafter.

The bottom of each compartment bin is constructed of four downwardly inclined walls 6 which terminate in a discharge opening 7 controlled by a sliding shutter 8. As shown, each of the three compartments discharge at a common point but it will be obvious that this might be very well arranged so that either six or nine compartments could discharge at a common point. It might also be mentioned that the series of compartments just described is arranged at such height that trucks, carts, and the like may drive under the discharge spouts 7 and be loaded directly from the bins.

In order that each of the series of bins may be progressively loaded I have provided a carrier 10 for cooperation with a chute 11 which conveys the material such as gravel, crushed stone, or the like to the bins. The carrier 10 comprises a pair of sprocket chains 12 spaced a distance equal to the width of the center compartment and cooperating with pairs of sprocket wheels 13 mounted on shafts 14. The chains 12 carry a number of scrapers or slats 15 of steel which are suitably spaced along the chains. Under the upper section of the carrier is located a table or platform 16 which is of a width equal to that of the central compartment and which extends above the top of all the bins of the series except the last one.

From the structure just described it will be apparent that the material fed through chute 11 will pass on to the platform 16 and will be carried along this platform by the carrier 10 until it reaches the end of the platform; from thence it will fall into the central compartment of the last bin. As this compartment fills up to the slots 4 and 5 the material will overflow into the compartments

3, and when these compartments are filled the material will build up in the central compartment until it reaches the lower section of the carrier 10. The material in the central compartment forms in effect a floor for the lower section of the carrier and material piling up on this floor will be drawn by the scrapers 15 into the next central compartment and so on until all compartments 10 of all the bins are filled.

In accordance with the patent statutes I have described what I now believe to be the best embodiment of the invention, but I do not wish to be understood thereby as limiting 15 myself or the scope of the invention, as many changes and modifications may be made without departing from the spirit of the invention; all such I aim to include in the scope of the appended claims.

20 What I claim as new and desire to secure by Letters Patent is:

1. In a device of the class described, a plurality of open-topped bins arranged in series and in juxtaposition, a platform spaced above said bins and extending over all but one of them, an endless conveyor arranged to travel along the length of the series of bins and having its upper run traveling over the surface of said platform and its 25 lower run traveling over the open tops of said bins.

2. In a device of the class described a plurality of open-topped, compartment bins arranged in series and in juxtaposition, a platform of a width equal to that of the central compartment and spaced above and extending over all but one of them, an endless conveyor arranged to travel along the length of the series of bins and having its upper run traveling over the surface of said platform 35 and its lower run traveling over the open tops of said bins, the compartments of each bin being provided with means for permitting an overflow of material from one of the compartments to the other compartments. 40

3. In a device of the class described a plurality of open-topped compartment bins arranged in series and in juxtaposition, a platform of a width equal to that of the central compartment and spaced above and extending over all but one of them, an endless conveyor arranged to travel along the length of the series of bins and having its upper run traveling over the surface of said platform 45 and its lower run traveling over the open tops of said bins, the compartments of each bin being provided with means for permitting an overflow of material from one of the compartments to the other compartments, and a valved discharge outlet at the bottom 50 of each compartment bin. 55
